WITNESS:

UNITED STATES PATENT OFFICE.

RAY A. HARRIS, OF NORTH WINDHAM, CONNECTICUT.

ARTICLE OF JEWELRY.

Application filed December 14, 1927. Serial No. 239,990.

This invention relates to an article of jewelry and has for an object the provision of an article which is both ornamental and useful, in that it serves both as an ornament 5 and as a perfume holder or container.

Another object of the invention is the provision of a perfume holder which includes an absorbent pad housed within a permanently closed container, the latter having 10 openings therein for the escape of perfume carried by the pad, the construction preventing loss of the contents of said container, or injury to the container from accidental opening occasioned by being caught in the 15 garments of the wearer, or from other causes, where a container is provided with a hinged lid or closure.

Another object of the invention is the provision of means for attaching the holder or 20 container in position for use, novel means being provided for securing the attaching means to the holder.

Another object of the invention is the provision of a combined lingerie clasp and 25 perfume holder which will act to support the neck portion of a garment in addition to its use as perfume holder, the garment supporting means being utilized as an attaching means for the holder.

With the above and other objects in view, 30 the invention further includes the following novel features and details of construction, to be hereinafter more fully described, illustrated in the accompanying drawing and 35 pointed out in the appended claim.

In the drawing:—

Referring to the drawing in detail where- 55 in like characters of reference denote cor- responding parts, the holder as shown com- 60 prises a base or back wall 10 and a front wall 11. The back wall is preferably flat while the front wall is curved or outwardly 65 bulged as shown in Figure 3 of the drawing so as to provide a container or holder for 70 the accommodation of an absorbent pad 12, which may be of felt or other suitable ma- 75 terial.

The edges of the wall 11 are permanently 80 secured to the wall 10 and for this pur- 85 pose, the wall 10 is provided with an annular flange 13 which surrounds the edge of the wall 11 and is bent over against the adjacent curved portion of said wall 11 so as 90 to clamp the walls together. The wall 11 is provided with openings 14 for the escape of perfume from the pad 12, and to provide means whereby perfume may be introduced into the container. These perforations are 95 preferably provided by making the wall 11 in the form of an ornamental scroll or filigree work.

In order to attach the holder to the clothing, there is provided a clasp which includes 70 a lever 15 and a lever 16. The levers 15 and 16 are pivotally secured together as shown at 17 and are provided at one of their ends with gripping jaws 18. The lever 16 is rigidly secured to the rear wall 10, while 75 the lever 15 is movable relatively and the jaws 18 are yieldingly held in closed position by means of a spring 19.

In order to secure the lever 16 to the back 80 or base 10 of the holder the said jaw is pro- 85 vided with spaced openings 20 and the back wall 10 has fingers 21 struck therefrom whose ends are bent over upon the outer 90 face of the lever 16 as shown at 22.

If desired the holder may be used as a 85 lingerie support and for this purpose, one end of the lever 15 carries a ring 23 which has attached thereto chains 24. The outer 90 ends of these chains are attached to clasps 25. These rings are attached to one of the levers 27 of the clasps 25; while the other lever 28 may be of ornamental appearance.

It will be apparent from the foregoing de- 95 scription and accompanying drawings that the invention provides a very useful as well 100 as an ornamental article of jewelry by pro- 105 viding a perfume holder which may be used with a number of different garments. This results in an economy of perfume over the usual method of applying the perfume di- 110 rectly to the garment and is especially de- 115 sirable with the use of expensive perfumes. In addition, it combines with a perfume holder a lingerie support with the use of the latter as an attaching means for the holder. 115

The invention is susceptible of various 120 changes in its form, proportions and minor 125 details of construction and the right is here- 130 in reserved to make such changes as properly fall within the scope of the appended claim. 130

Having described the invention what is claimed is:—

5 An article of jewelry comprising an ornament in the form of a container having openings therein, means to detachably secure the lower end of the container to the front of a garment at the top of the latter, chains having their inner ends secured to the top of the container, and means at the outer ends of the chains for detachable connection with the shoulder straps of a garment to support said container in upright position and hold said shoulder straps in place. ¹⁰

In testimony whereof I affix my signature.
